his Attorney.

UNITED STATES PATENT OFFICE.

PETER REINHARDT, OF ST. PAUL, MINNESOTA.

COMBINATION HEATER AND COOKER.

1,396,464.

Specification of Letters Patent.

Patented Nov. 8, 1921.

Application filed October 8, 1920. Serial No. 415,567.

To all whom it may concern:

Be it known that I, PETER REINHARDT, a citizen of the United States, residing at St. Paul, in the county of Ramsey and State 5 of Minnesota, have invented certain new and useful Improvements in Combination Heaters and Cookers, of which the following is a specification.

This invention relates to gas heaters, and 10 more particularly to the small portable type usually adapted to be connected with a source of gas supply such as the ordinary jet, by means of a flexible tube, not shown.

An object of my invention is to provide, 15 in a heater of the class described, improved means, whereby a portion of the heated air is caused to be intercepted and discharged at a particular position on the heater, where small utensils may be so placed as to become 20 heated by the air as it rises from the discharge openings, for the purpose of cooking food or heating water and the like.

A further object of the invention is to provide a heater of the class described, which is 25 of simple, cheap construction, serving simultaneously as a heater, and cooking stove, the parts being arranged so as to effect two separate constantly active hot air discharges, when in use.

30 To this end, the invention consists in the construction, combination and arrangement of parts hereinafter described and claimed.

In the drawings forming part of this 35 specification,

Figure 1 is a perspective view of the invention.

Fig. 2 is a vertical sectional view on line 2-2 of Fig. 1, and

Fig. 3, is a horizontal sectional view on 40 line 3-3 of Fig. 1.

A designates a rectangular box-like casing or shell formed with a flat top 1, a bottom 2, side walls 3 and 3', and a back 4. B designates a curved deflector plate secured 45 by means of bolts 4' to the wall 4, and extending laterally between the side walls and spaced above and below, a distance from said top and bottom, so as to form a hollow floor and a hollow roof effecting air 50 spaces or chambers C and C', said chambers being symmetrical about a longitudinal vertical plane located central of the casing. The top 5 and bottom 6 of the deflector plate which constitutes a lining for the casing, 55 is curved toward the front of the latter in a manner to form an arcuate floor b

and ceiling c for the space within the lining which constitutes the combustion chamber. At its front the casing is formed with an upper and lower front wall 7 and 8 respectively, said walls joining with the walls 1 and 2 respectively and with the horizontal long edges of the lining to completely inclose the air spaces C and C'. The walls 7 and 8 are spaced vertically to form a long 60 main hot air front outlet opening D of uniform height extending across the front of the casing and being located nearer the bottom to the top of the casing. Supported by the walls 3 and 3' so as to extend from 65 one to the other, horizontally of the casing at a position midway between the front and rear walls of the latter nearer the ceiling c of the lining than to the lower edge of the wall 7 is the burner E. The burner consists 70 of a horizontally disposed pipe 10 closed at the end supported in the wall 3, and extending through the wall 3', and having at its outer end a suitable gas valve 11 having a ribbed cone end 11', whereby the supply 75 of gas may be cut off.

Adjacently surrounding the pipe 10 and cutting through the wall 3' are a plurality of perforations 12 which constitute air inlets.

Along its upper side the burner pipe 10 is perforated at regular intervals with a row of jet openings 13, over which positioned in direct vertical alinement is a row of vent openings 14, cutting through the lining B, said openings being spaced at longer intervals and cut to larger diameter. Alternating individually with the vent openings 14, and arranged in a row directly above the latter are the discharge openings 15, cut through the top plate 1 of the casing. Obviously, the aggregate area of either the vents or the discharge openings amounts to but a fraction of that of the opening D.

A suitable rail 16 spaced a distance above 100 the top plate 1, serves as a support for large utensils (Fig. 2) and a guard against displacement for the smaller ones.

In use, the larger part of the heated air will be discharged through the main discharge opening D in the usual way, the balance passing through the comparatively small vents 14 into the chamber C, and thence, as indicated by the arrows through the secondary discharge openings 15. By alternating the openings 15 with the vents 14, the air is deflected from a straight course and

thereby retarded in its movement, thus assisting in forcing the larger volume of air through the main discharge opening D.

By having the burner jets nearer the perforations in the lining than to the opening D, the entry of the heated air into said perforation is facilitated.

The hollow floor of the device serves at once as an insulating medium whereby the air within is protected against cooling prior to passing through the opening D, and as a protection to the floor of room against scorching.

I claim:

15 In a combined heater and cook stove, the combination, a rectangular long casing having flat surrounding outer walls and a flat top and bottom, said top having a row of holes, and the front wall having a long 20 narrow heat discharge opening for discharging heat into the room, said opening extending to the end walls and being located as a whole, nearer the bottom than the top of said casing, a lining sheet for the 25 casing extending longitudinally of the casing to the end walls thereof, and transversely of the casing in a curve from the upper edge of said opening upwardly to a point adjacent the top, and downward into 30 contacting relation with a vertically central point on the rear wall and then adjacent to

a point longitudinally central of the bottom and terminating at the lower edge of said opening, whereby is formed an upper and lower air chamber located respectively directly under the top, and immediately above the bottom of the casing, the transverse section of said air chambers being approximately symmetrical about a vertical longitudinal plane central of the casing, whereby the heated air will be evenly distributed on either side of said plane in said chambers, a row of perforations in the top of said lining arranged longitudinally central of the casing, and being appreciably smaller than said holes in the top of the casing, a gas burner having a row of gas outlets extending longitudinally centrally of the casing and located nearer said perforations than to the upper edge of said heat discharge opening, so as to form an upper relatively deep area between said burner and said opening, whereby to facilitate the entry of the rising heated air from said jets through said perforations in the lining and said holes in the top of the casing, and air inlets in the end wall of said casing adjacently surrounding said burner, said air inlets being wholly above said heat discharge opening.

In testimony whereof I affix my signature.

PETER REINHARDT.
